UNITED STATES PATENT OFFICE.

WILLIAM HOMAN, OF NEW YORK, N. Y.

REPLY POSTAL-CARD.

SPECIFICATION forming part of Letters Patent No. 339,890, dated April 13, 1886.

Application filed November 9, 1885. Serial No. 182,961. (No model.)

To all whom it may concern:

Be it known that I, WILLIAM HOMAN, of New York city, in the county and State of New York, have invented a certain new and 5 useful Improvement in Reply Postal-Cards, of which the following is a specification.

There is a demand in correspondence by post for a means of providing a return postal-card attached to the principal one, both to be prepaid by the original sender. Many efforts have been made to supply this want. Among other schemes has been folding a sufficiently large piece of paper or pasteboard and attaching the free edges temporarily together by interlocking devices. All such previously 15 known to me were open to objections.

I have discovered and reduced to practical form a construction in which one part is wider than the other, equipped with a locking-tongue, 20 and the stiffness of the card itself is made available to hold the free edges in the locked condition. It will serve when folded either way. It is eminently easy to operate.

One objection to all the previous devices is 25 that they are difficult to operate. It is essential to the success of a reply postal-card that it shall be extremely simple. Another objection to the former devices is the mutilating of the return postal-card. My plan leaves this 30 important part—the part which has to endure the passage through the mail in both directions—without slotting or other mutilation. It is a plain, uncut, and unweakened card.

My reply postal-card may be returned by 35 simply detaching the previously locked free edges and folding in the opposite way, using the same locking means to engage the parts in the reverse position as was previously employed to hold them locked in their original 40 position. Another mode of using the invention is to tear apart the two parts on the folding-line, letting the recipient retain the original part and use the other part alone for the return message. In such case the latter may 45 be in size and in all respects an exact fac-simile of an ordinary single postal-card. It is unmutilated and unmarked by its previous experience.

The accompanying drawings form a part of 50 this specification, and represent what I consider the best means of carrying out the invention.

Figure 1 is a face view of the postal-card in its outward journey, and Fig. 2 is a central cross-section of the same. Fig. 3 represents 5 one face of the complete postal-card in its extended condition either before or after it is used. Fig. 4 is a similar view of the opposite face. Fig. 5 shows the reply portion detached from the other. 60

Similar letters of reference indicate corresponding parts in all the figures where they occur.

A is the main body or principal postal-card, the part which serves to carry the address, 65 and also, by preference, to carry the message on its outward journey. In such case the message is written on the reverse side of the principal part, which is the inside when the return part is folded upon it. This principal part 70 has a curved slot, a, produced by any suitable cutting instrument. The portion of the card embraced within this curve may be deflected by the thumb or finger to either side.

B is the other part—that which is to serve 75 for the reply. A and B constitute two parts of a single card. They are partially separated by a line of perforations or analogous means, c c. It is easy to fold on the line c either in one direction or the other. The part A is 80 wider than the part B, and the curved slot a is so located that on deflecting the tongue a' slightly it is easy to engage the edge of B under it, and the parts will remain locked. The face bearing the postage-stamp and adapted to 85 receive the address is on one side of the part A and on the opposite side of the part B.

Whether my reply postal-card is folded one way to serve for the outgoing trip, or folded the other way to serve for the return trip, it 90 is easy to lock the free edges together by the tongue a' engaging the edge of the part B. The stiffness of the material should be sufficient to hold the part B extended, so that its edge will remain locked under the tongue a' 95 after it has been properly engaged. The receiver can, if he prefers, tear across on the line c, and use only the return part B for the return message. The name of the sender may be written, or, in case many are provided, can be 100 printed in the proper position on the return part B before being mailed by the sender.

My postal-card should be used one way or the other for the return message, according as

the original sender has placed his message for the outgoing journey on one part or the other. If he folds and locks the parts first and writes his message on the back of the part B, the recipient must send both parts back, folding the other way, and writing his message on the back of the original card; but if, as may be generally preferable, the sender writes his message on the back of A and folds and locks B over it, then the recipient will write his answer on the back of the part B, and send both parts back, or only the part B, as he may elect.

Modifications may be made in the forms and proportions. I can use two of the slots *a* and two of the tongues *a'*.

Instead of the curved form of the slot *a*, I can use a rectangular form. I esteem it important that the slot *a* be of such form as to produce a strong tongue, *a'*. The part B will engage by its edge, in the manner shown, under tongues of widely varying forms and sizes. The form shown is preferable.

I design to use a similar card as an advertising medium, and adapted for distribution by mail or otherwise. Such card I design to 25 make subject-matter for a separate application.

I claim as my invention—

The reply postal-card described, unequally divided by a folding-line of perforations, *c c*, or analogous means, the part A being wider 30 than B, and provided with a tongue, *a'*, arranged to engage the edge of the part B when folded, as herein specified.

In testimony whereof I have hereunto set my hand, at New York city, this 2d day of November, 1885, in the presence of two subscribing witnesses.

WM. HOMAN.
